Inventor:
Samuel M. Stein
By Fisher, Towle, Clapp & Evans,
Attys.

UNITED STATES PATENT OFFICE.

SAMUEL M. STEIN, OF CHICAGO, ILLINOIS, ASSIGNOR TO A. STEIN & COMPANY, OF CHICAGO, ILLINOIS, A CORPORATION.

DISPLAY REEL.

Application filed December 27, 1921. Serial No. 524,852.

To all whom it may concern:

Be it known that I, SAMUEL M. STEIN, a citizen of the United States, residing at Chicago, in the county of Cook and State of Illinois, have invented certain new and useful Improvements in Display Reels for Ribbons and the like, of which I declare the following to be a full, clear, and exact description, reference being had to the accompanying drawing, forming part of this specification.

The present invention has for its object to provide a simple, cheap and effective reel for ribbon, tape, elastic and like strip material, which shall be of such construction that it will stand in vertical position and so effectively display the ribbon or like material and the advertising matter appearing upon the sides of the reel. The invention consists in the features of novelty hereinafter described, illustrated in the accompanying drawing, and particularly pointed out in the claims at the end of this specification.

Fig. 1 is a perspective view of a reel embodying my invention.

Fig. 2 is a view in vertical section on line 2—2 of Fig. 1.

Fig. 3 is a view in vertical cross section on line 3—3 of Fig. 2.

The body of the reel is composed of two side plates A and A' that are united by a hub or core B, preferably formed of wood. The side plates A and A' are formed of some sheet material such as cardboard, celluloid, veneer or metal, and as shown, are united to the core or hub B by staples C. Obviously, however, the hub or core B may be glued or otherwise attached to the side plates A or A'.

Upon the outer faces of the side plates A and A' there will be conspicuously displayed advertising matter such, for example, as indicative of the character of the material wound upon the reel, its trade-name and the like. The hub or core B is formed with a hole b extending therethrough and in the side plates A and A' are formed holes that coincide with the hole b in the hub or core B. This arrangement will permit a pencil or like article to be inserted through the reel

when the material is to be withdrawn there-

from. Preferably around the core or hub B is placed a loose sleeve D that may be formed of cardboard, metal or the like, upon which sleeve the strip of ribbon, elastic, tape or the like will be wound.

One and preferably both of the side plates A and A' are provided with depending portions such as feet a and a' preferably formed integral therewith, which enable the reel to be stood in vertical position, as shown in Fig. 1, upon a counter (such as indicated at W), a show-case or the like; and when in such position the advertising matter upon the outer faces of the plates A and A' will be conspicuously displayed and the color and character of the material wound upon the reel will also be disclosed.

When the strip material, such as ribbon or the like, is to be withdrawn from the reel, the reel can be readily grasped by the hand of the salesman and the desired amount of material can be removed therefrom.

Having thus described my invention, what I claim as new and desire to secure by Letters Patent is:

1. A reel of the character described comprising a pair of disks or side plates of thin sheet material and a connecting core of much less diameter at all points than said side plates, said core being united at its ends to said side plates, said side plates having formed integral therewith at the bottom depending feet adapted to sustain the reel in vertical position.

2. A reel of the character described comprising a wooden core of uniform diameter from end to end, and side plates formed of thin sheet material of considerably larger diameter than said core, said side plates being attached to the ends of said core and being provided at their bottoms with depending portions whereby the reel will be caused to stand in vertical position.

3. A reel of the character described comprising a wooden core, side plates of thin sheet material, and staples connecting said side plates to the ends of said core, said side plates being provided with integral depending feet.

SAMUEL M. STEIN.
